UNITED STATES PATENT OFFICE

GUSTAV E. JANSSON, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

SYNCHRONIZING SWITCH

Application filed March 30, 1928. Serial No. 266,065.

This invention relates to electric switches as synchronizing switches which are adapted to connect together two separately energized sections of a high tension alternating current line when the two sections are in synchronism with each other.

One of the objects of the present invention is the provision of a synchronizing switch which carries high tension condensers that are connected separately to the terminals of the switch and to each other and to the ground and have intermediate terminals which are at some voltage intermediate line voltage and ground, the condensers serving as surge arresters to prevent surges, which frequently occur during the normal operation of the line and also during the operation of the switch when the lines are not properly synchronized, from damaging the high tension bushings of the switch; the condensers also serving as electrostatic potential transformers and providing at their intermediate terminals reduced voltages which are proportional to the line voltages for the primary purpose of actuating synchronizing indicators to indicate the synchronous condition of the line. The combination of the synchronizing switch with such condensers, as an integral structure, constitutes a further object of the invention.

Another object of the invention is generally to improve the construction of synchronizing switches.

Fig. 1 is an elevation of a synchronizing switch embodying the invention.

Fig. 2 is a sectional elevation through one of the condensers of the switch.

Fig. 3 is a diagram of the circuit connections of the switch, condensers and the synchronism indicator.

The synchronizing switch herein shown is of the oil immersed type and comprises a casing having a cover 10 and an oil receptacle 12 in which the separable contact members are enclosed. The switch is provided with a pair of terminals comprising high tension bushings 14 and 16 carried by the cover 10 and extended into the oil receptacle and having conducting studs provided at their lower ends with fixed contact mem-

bers 18. A movable switch member 20 cooperates with said fixed contact members to control the circuit through the switch. One of the separately energized line sections 22 is connected with one of the switch terminals 14 and the other separate line section 24 is connected with the other switch terminal 16.

In accordance with this invention, the switch is provided with two condensers 26 and 27 both of which are carried by and connected electrically to the cover 10 and one of which is disposed adjacent and as close as practicable to one switch terminal 14 and the other to the other switch terminal 16. The condensers are similar.

Each condenser comprises an insulating porcelain shell 28 of suitable height having petticoats 30 thereon. The lower open end of the shell is secured to and is received within the upstanding annular flange 32 of a plate 34 which forms a closure for the lower open end of the porcelain shell. The upper open end of the shell is covered by a cap 36.

The condenser comprises a plurality of condenser units 38, four being here shown. Each condenser may comprise a cylindrical metal shell which encloses the condenser plates and their dielectric and forms one terminal of the condenser unit. An insulating bushing 40 upstands from one end of the unit and is provided with a terminal 42 that constitutes the other terminal of the unit.

The capacity of each condenser unit may be any desirable value and the condenser units may be connected together in any desirable manner. As here shown, the four condenser units are arranged in superposed order within the shell 28 and are connected with the bottom of the metal shell of the next upper unit. The shell of the lowermost unit is electrically connected with the plate 34, which forms a low tension terminal of the condenser. The insulated terminal of the uppermost condenser is connected to the cap 36, which thus forms the other, and high tension, terminal of the condenser.

Separate low voltage terminals 43 and 44 are brought out through the wall of the shell

28 and are respectively connected to the insulated terminals of the lowermost and the next upper condensers so that the voltage between said terminals and the ground is 5 respectively the voltage across the lowermost condenser and the sum of the voltages across the two lowest condensers.

The condensers 26 and 27 are mounted on 10 outstanding brackets 46 which are or may be integral with the cover 10 and the plates 34 of the condensers are bolted to said brackets and thus are electrically connected therewith. The condensers are thus disposed as close to the terminals 14 and 16 of the 15 switch as is practicable and are connected to the lines 22 and 24 by conductors 48 ahead of the switch terminals.

The casing of the switch is grounded by a connection not shown.

20 The capacity of the condensers 26 and 27 is sufficiently great, and the condensers are very close to the switch terminals to absorb dangerously high voltage surges that may be present in the lines 22 and 24, caused either 25 during normal operating conditions of the line or by the closing of the switch when the lines are not in sufficiently close synchronism. The condensers, by absorbing or drawing off 30 the peak of the voltage surges, thus protect the insulating bushings of the switch against break down.

A synchronism indicator 50 which may be 35 of any well-known type is adapted to be connected by leads 52 and 54 to a selected one of the terminals 43, 44 of the two condensers 26 and 27 respectively and also by a lead 56 to the grounded and interconnected ends of the condensers, whereby it can indicate when the 40 line sections are in synchronism and when the switch can be closed safely.

The plurality of low voltage terminals with which each condenser is provided permits the selection of a potential suitable for operating the synchronism indicator.

45 The low potential terminals can also be utilized for the energization of other instruments and apparatus such as voltmeters; and the capacity of the condenser is sufficient to supply a substantial amount of power, so that 50 relays and other low-power consuming apparatus can be operated.

By having the switch provided with a condenser for each terminal thereof, the line on both sides of the switch is protected against 55 surges, even when the switch is open.

I claim:

1. A high tension synchronizing switch having insulated switch terminals and a pair of surge absorbing condensers carried by the 60 switch in close proximity to said terminals, said condensers having high tension terminals connected each to the circuit of a switch terminal and low tension terminals connected together and each having an intermediate 65 low voltage terminal.

2. A synchronizing switch comprising an enclosing casing having insulated terminals, condensers carried by said switch casing in close proximity each to a switch terminal and having high tension terminals which are adjacent and are connected to said switch terminals and having lower terminals which are connected to said switch casing. 70

3. A synchronizing switch comprising an enclosing casing having insulated terminals, condensers carried by said switch casing in close proximity each to a switch terminal and having high tension terminals which are adjacent and are connected to said switch terminal and having lower terminals which are connected to said switch casing, each of 75 said condensers having an intermediate low tension terminal. 80

4. A synchronizing switch comprising a casing having upstanding insulated terminals, upstanding insulating shells carried by said casing each of which is in close proximity with one of said switch terminals and has an upper high tension terminal, each shell having a plurality of connected condenser units contained therein which are connected respectively to said high tension terminal and to said casing and an intermediate low tension terminal connected to one 90 of said condenser units. 95

5. A synchronizing switch comprising a casing having upstanding bushings provided with upper exposed switch terminals and upstanding insulating shells carried by said casing, each of which is in close proximity 100 with a separate one of said bushings and has an upper high tension terminal located in close proximity with one of said switch terminals, each of said shells having an attaching plate at its lower end which is connected 105 with the casing and constitutes a low tension terminal, a plurality of connected condenser units contained in each shell and connected between said high and low tension terminals and each of said shells having an intermediate low tension terminal connected between 110 said condenser units. 115

6. The combination of two separately energized sections of a high tension alternating current line, apparatus for connecting said sections together when they are in synchronism comprising a switch having two terminals each connected with a separate one of said line sections, and grounded condensers each separately connected to a separate one of said sections at a separate switch terminal, said condensers having such high capacity as to absorb surges that may be set up by the closing of the switch when the sections are not in precise synchronism and to prevent 125 such surges from going out onto said sections. 120

7. The combination of two separately energized sections of a high tension alternating current line, apparatus for connecting 130

5 said sections together when they are in synchronism comprising a switch having two terminals each connected with a separate one of said line sections, and grounded condensers each separately connected to a separate one of said sections at a separate switch terminal, said condensers having such high capacity as to absorb surges that may be set up by the closing of the switch when the
10 sections are not in precise synchronism and to prevent such surges from going out onto said sections, said condensers also having intermediate low-potential terminals that provide a low voltage that is a function of
15 the section-voltage.

20 In testimony whereof, I have signed my name to this specification.

GUSTAV E. JANSSON.
